ARTICLE CARRIER FOR VEHICLE INTERIOR

Stephen R. Stewart, Upland, Calif.
(3122 Schweitzer Drive, Topanga, Calif. 90290)

Filed June 10, 1971, Ser. No. 152,005

Term of patent 14 years

Int. Cl. D12—16
U.S. Cl. D14—6 T

FIG. 1.

FIG. 2.

FIG. 3.

FIG. 4.

FIG. 5.

FIG. 6.

FIG. 1 is a front elevational view of an article carrier for vehicle interior, showing my new design;

FIG. 2 is a top view thereof;

FIG. 3 is a bottom view thereof;

FIG. 4 is a rear view thereof;

FIG. 5 is an end view thereof; and

FIG. 6 is a sectional view taken at line 6—6 in FIG. 1. The end not shown is a mirror image of the end shown in FIG. 5.

I claim:

The ornamental design for an article carrier for vehicle interior, as shown and described.
